Theodore W. Gillagne, of Philadelphia, Pa.

Assignee to Savery & Co. of same place.

Letters Patent No. 1225, dated April 3, 1860.

The schedule referred to in these Letters Patent and making part of the same.

To all whom it may concern:

Be it known that I, Theodore W. Gillagne, of the City of Philadelphia, and State of Pennsylvania, have invented or produced a new and original Design for Fire-dogs; and I do hereby declare that the following is a full and exact description of the same, reference being had to the Annexed drawing, making a part of this Specification, and to the letters of reference marked thereon.

For the purpose of nominal distinction, I call this design for fire-dogs, "The Globe pattern." It consists of a combination of ornamented scrolls, with foliage, a shield, and a three-faced pillar, surmounted by a globular ornament, as hereinafter described, the whole forming together the general configuration seen in the drawing, and adapted to be cast of metal to serve as the front part of a fire-dog.

The scrolls A, A, form the feet and legs, each being ornamented with the beads 1-1, and leaves 2-2, and also connected, respectively, with the scrolls B, B, and the lower extremities C, of the shield D. The shield D, is ornamented with shell points 3-3, at its two sides and, over its upper edge, hang the leaves 4-4, whose bases are intertwined in another series of leaves 5-5, which point upward. Rising from a-

Ms 1225

midst these leaves 5-5, is the three-faced pillar E, which is ornamented with scrolls, or pending vine foliage 6.

The pillar, E, is capped with the series of pendant leaves 7-7 whose bases run into or terminate upward in an urn ornamented with the creeping foliage 8-8 and upon the top of which urn rests the globe F.

(What I claim as my invention or production, and desire to secure by Letters Patent is—

The configuration and ornamentations arranged and combined together as herein set forth and described, as a new and original design for a fire-dog.

Witnesses.

Benj Morrison, {
George Pfeiffer. }

Theodore W. Gillagore.
